UNITED STATES PATENT OFFICE.

SYLVESTER MOZROLL, OF ROCHESTER, NEW HAMPSHIRE.

BRACKET.

1,187,366.

Specification of Letters Patent. Patented June 13, 1916.

Application filed March 22, 1916. Serial No. 85,948.

To all whom it may concern:

Be it known that I, SYLVESTER MOZROLL, a citizen of the United States, residing at Rochester, in the county of Strafford and State of New Hampshire, have invented new and useful Improvements in Brackets, of which the following is a specification.

The present invention relates to improvements in the construction of curtain brackets.

An object of the invention is to produce a shade roller support or bracket which can be attached to the window casing without defacing or marring the same at any point of contact with the said casing and which will securely and effectively support the roller.

Another object of the invention is to construct a shade roller support or bracket of three elements comprising a hanger which is adapted to be inserted between the top of the window casing and the surface to which the casing is secured, a back plate which engages with the hanger and which rests upon the outer face of the window casing and a bracket proper which is detachably connected with both the hanger and with the back plate but which engages with the same in such a manner as to lock the said plate and hanger as well as to force the engaging member of the hanger into more tight engagement with the window casing and to force the hanger against the outer face of the casing without permitting the bracket to contact with the said casing when the weight of the curtain roller is upon the bracket.

With the above and other objects in view, the improvement resides in the construction, combination and arrangement of parts set forth in the following specification and falling within the scope of the appended claims.

In the drawings: Figure 1 is a perspective view illustrating the application of my improvement, Fig. 2 is a greatly enlarged central vertical sectional view taken through one of the roller supporting members or brackets, Fig. 3 is a detail view illustrating the manner in which the bracket is arranged upon the hanger and the back plate before the parts are operatively assembled, Fig. 4 is a perspective view of the hanger member, Fig. 5 is a similar view of the back plate, and Fig. 6 is a similar view of the bracket or roller supporting bracket.

Referring now to the drawing in detail, the numeral 1 designates an ordinary window casing having at its opposite ends a shade curtain support or bracket 2 which is constructed in accordance with my invention.

Each of the brackets or supports is of a similar construction and includes a hanger 3, a back or protective plate 4 and a bracket or curtain roller support proper 5.

Each of the elements comprising the improvement is preferably constructed of spring material, such as light strong steel but, of course, the same may be formed of any desired material. The hanger 3 comprises an arched or curved member having its lower end formed with an inturned portion or foot 6 and its upper end bent upon itself to provide an angular lip 7, and this lip is adapted to be inserted between the casing 1, at the upper and inner edge thereof and to engage with the plaster or other surface to which the casing is secured. The curved or arched portion of the hanger will, of course, be arranged over the face of the top bar of the casing and while its foot 6 may be adapted to exert an inward tension toward the said casing, the said foot does not at any time contact with the casing.

The back or protective plate 4 is wider than the hanger 3 and has its upper edge notched, as at 8, to receive the upper portion of the hanger outward of its lip 7. The opposite or lower end of the plate 4 is formed with an angular extension 9 which is adapted to underlie the angular end or foot 6 of the hanger 3 and which may be forced into contact with the said foot in a manner which will presently be described. The plate 4 is provided, at a suitable distance above its angular end 9, with a transverse notch 10.

The bracket or shade roller support proper, 5, is preferably constructed from a single sheet of suitable material and includes spaced sides 11—11, the said sides at their outer ends being provided with notches or openings 12 to receive the pin-tle or the shaft of the spring of the shade roller 13. The sides 11 are connected by a top 14, the said top being arranged at an inclination with respect to the said ends of the sides which are provided with the notches or openings 12 and this top has what may be termed its forward end ter-

minating a suitable distance to the rear of said notches or openings 12, providing what I will term a shoulder and which is indicated by the numeral 15, between the 5 outer or straight portions of the sides 11. The top extends a suitable distance beyond the inner ends of the sides 11, and the said projecting portion is notched, as at 16, and this notch is adapted to be received in 10 the groove 10 of the member 4, the arms or lugs 17 provided to the opposite sides of the notch engaging the opposite edges of the member 4. The bracket member 5 is first arranged upon the back plate 4 in a 15 manner as just described, and the hanger 3 is brought between the forward ends of the spaced sides 11 of the bracket. The bracket is then swung so that its shoulder 15 will contact with the foot 6 of the hanger, and 20 when the shade roller is arranged upon the bracket members 5, the weight thereof will cause the said members 5 to tilt or swing downwardly causing the shoulder 15 to force the foot 6 of the hanger into contact 25 with the angular end 9 of the back or protector plate 4. This, it will be noted, will force the plate 4 into contact with the outer face of the casing and also cause the lip 7 of the hanger to more tightly engage with 30 the inner edge of the casing.

From the above description, taken in connection with the accompanying drawings, the simplicity of the device as well as the advantages thereof will, it is 35 thought, be perfectly apparent to those skilled in the art to which such invention appertains without further detailed description.

Having thus described the invention, 40 what I claim is:

1. In a means for supporting a shade roller or the like upon a window casing, including an arch-shaped hanger having one of its ends bent to provide a lip which 45 is inserted between the casing and the surface to which the casing is secured, an L-shaped plate adapted to rest upon the outer face of the casing, a bracket member including an element comprising spaced 50 sides, a top connecting the sides for a portion of their length, said top having its inner end trunnioned upon the plate adapted to be swung upon the arch-shaped hanger to engage with the lower end there-

of to force the said lower end into contact 55 with the angular end of the plate.

2. In a means for supporting a curtain roller upon a window casing, an arch-shaped hanger having one of its ends bent to provide a lip which is arranged between 60 the inner face of the casing and the surface to which the casing is secured, the opposite end of the hanger being formed with an in-turned foot, an L-shaped plate arranged to engage with the face of the casing, and to 65 have its angular portion underlie the foot of the hanger, said plate having a transverse groove, a bracket member including spaced sides and an angular top connecting the sides for a portion of their length, 70 the inner edge of the top adapted to be brought to engage with the foot of the hanger to force the said foot to contact with the angular end of the plate.

3. In a means for supporting a shade 75 roller upon a window casing, a hanger comprising a flat spring member which is curved and which has its inner end formed with a lip that is adapted to be arranged over the casing and to be inserted between 80 the said casing and the surface to which the casing is secured, the opposite end of the hanger being formed with an in-turned foot, a plate arranged over the face of the casing, said plate having its upper edge 85 notched to engage with the hanger and its lower edge formed with an angular extension which underlies the foot of the hanger, said plate having a transverse groove arranged above its angular end, a 90 bracket member, said bracket including spaced sides, an inclined top connecting the sides for a portion of their length and extending beyond the sides, said extension being notched, said grooved portion adapted 95 to be received in the groove of the plate, and the opposite end of the top adapted to contact with the foot of the hanger to force the same toward the angular end of the plate to hold the plate and hanger associated.

In testimony whereof I affix my signature in presence of two witnesses.

SYLVESTER MOZROLL.
